DESIGN FOR A DRESS ENSEMBLE

Clement Andre-Ani, St. Louis, Mo.

Application March 9, 1939, Serial No. 83,464

Term of patent 3½ years

To all whom it may concern:

Be it known that I, Clement Andre-Ani, a citizen of the United States, residing in the city of St. Louis, State of Missouri, have invented a new, original, and ornamental Design for a Dress Ensemble, of which the following is a specification, reference being had to the accompanying drawing, forming a part thereof, in which:

Fig. 1 is a front view of a dress ensemble showing my design.

Fig. 2 is a front view of the dress member of the ensemble shown in Fig. 1.

Fig. 3 is a rear view of Fig. 2 shown on a reduced scale.

Fig. 4 is a rear view of the jacket member of the ensemble shown in Fig. 1 on a reduced scale.

I claim:

The ornamental design for a dress ensemble, substantially as shown.

CLEMENT ANDRE-ANI.
